MILK CARTON HOLDER OR SIMILAR ARTICLE

John H. Garvin, Janesville, Wis.

Application August 23, 1954, Serial No. 31,961

Term of patent 7 years

(Cl. D58—26)

To all whom it may concern:

Be it known that I, John H. Garvin, a citizen of the United States of America, residing at Janesville, in the county of Rock and State of Wisconsin, have invented a new, original, and ornamental Design for a Milk Carton Holder or Similar Article, of which the following is a specification, reference being had to the accompanying drawing, forming a part thereof.

In the drawing:

I claim:

The ornamental design for a milk carton holder or similar article, as shown.
